(57) **CLAIM**

The ornamental design for an inflatable chair, as shown and described.

DESCRIPTION

FIG. 1 is a front perspective view of an inflatable chair; FIG. 2 is a back perspective view thereof;

FIG. 3 is a front view thereof;

FIG. 4 is a back view thereof;

FIG. 5 is a top view thereof;

FIG. 6 is a bottom view thereof;

FIG. 7 is a right side view thereof; and,

FIG. 8 is a left side view thereof.

The broken lines in the figures are for the purpose of illustrating portions of the inflatable chair, which form no part of the claimed design.

1 Claim, 8 Drawing Sheets
